UNITED STATES PATENT OFFICE

2,399,080

GOVERNOR

Stanley M. Udale, Detroit, Mich., assignor to
George M. Holley and Earl Holley

Application October 15, 1945, Serial No. 622,452

1 Claim. (Cl. 123—103)

The object of this invention is to govern in two stages:

1st stage—normal wide-open operation to act at say 2000 revolutions per minute at full load;

2nd stage—to automatically reduce speed at light load to say 1000 revolutions per minute.

Figure 1 shows the preferred form of my invention.

Figure 2 shows an alternative modification.

In Figure 1, 10 is the air entrance, 11 is a fuel nozzle discharging into the throat of a venturi 12 of a carburetor, the float chamber of which is not shown. A throttle 14 controls the mixture outlet and a lever 16 connected to a rod 18 automatically controls the throttle 14. A manual control 17 is available for pushing the throttle into its closed position, a spring 19 pushes the throttle open, a diaphragm 80 is engaged by the spring 19 and engages with the rod 18, a chamber 20 located to the right of diaphragm 80 is connected through restriction 72 with the inlet manifold 34 through a pipe 22. This pipe 22 and a pipe 24 connected thereto connect the chamber 20 with a passage 26 in a rotating element 68, driven by the shaft 70 at engine speed or some fraction of engine speed. A weight 28 responds to centrifugal force and controls an opening 30 by means of a needle 32. The passage 26 communicates with the opening 30 through drilled passages in the weight 28. A rod 52 is connected to the weight 28 and to a tension spring 44 anchored to a second diaphragm 42. A compression spring 48 pushes the diaphragm to the left against a spring stop 50.

A second passage 38 connects the inlet manifold 34 through a passage 36 with a chamber 40.

Description—Figure 2

In Figure 2, the centrifugal weight 74 is pushed off its seat by a spring 73. As before, needle 32 controls an atmospheric opening 30; as before, the passage 26 communicates with the atmospheric opening 30 through drilled passages in the weight 74. The rod 56 is hooked over a lever 58. Lever 58 is pivoted at link 62 and is anchored from below and is supported by a tension spring 57, connected to the lower end of the lever 58, and the compression spring 78 engaging with the weight 74 insures that a maximum effort keeps the weight 74 to the left at low suction in a chamber 56. The chamber 56 containing these elements is formed by the diaphragm 60. A stop 66 limits the movement of diaphragm 60 to the right. An arm 89 bolted to the center of the dia-

phragm 60 engages with the stop 66, which is located on the upper end of a spring 81.

Operation—Figure 1

Assume that the rod 17 is pushed over to the left so as to permit the throttle 14 to respond to the diaphragm 80, to the spring 19 and to the governor. Then, first the throttle 14 opens as atmospheric pressure acts through 30, past needle 32, through the weight 28, down the passage 26, across the pipe 24 to the chamber 20. Hence, the spring 19 pushes the rod 18 to the left and opens the throttle 14 when there is a low suction in manifold 34, that is, when there is a heavy load on the engine.

At high speed, the weight 28 flies over to the right, closes the opening 30, and the diaphragm 80 responds to the depression in the manifold 34, which rapidly increases as the throttle 14 closes, so much so that the suction in chamber 40 moves diaphragm 42 to the left, reducing the tension in the spring 44. Hence, at idle, a low speed is reached before the weight 28 is lifted off the seat 30, and this low speed, at which the weakened spring 44 moves the weight 28 to the left, is the low speed at which the engine idles. When load is applied, the suction in 34 is reduced and high-speed governing is restored. This governor can thus be set for a governed speed under full load of say 2000 revolutions per minute and at 1000 revolutions per minute, the engine would idle at no load.

Operation—Figure 2

When the critical speed is reached at full load, the weight 74 compresses the spring 73, stretches the spring 57 and closes the opening 30. When the high suction, corresponding to no load, acts on the diaphragm 60, it moves to the right and the upper end of lever 58 also moves to the right; hence, only the spring 73 remains in action to keep the weight 74 from moving the needle 32 to the right to close the opening 30. Hence, at a low speed, say 1000 revolutions per minute, the weight 74 closes the opening 30 and the no-load governed speed is 1000 revolutions per minute as compared with full-load governed speed of 2000 revolutions per minute.

The weight 74 can be of brass and the center portion of diaphragm 60 can be aluminum or of magnesium, as can the lever 58, link 62 and rod 54, so that the centrifugal effect on the diaphragm link and lever may be small as compared with the centrifugal effect of the weight 74.

What I claim is:

In a centrifugal governor for an internal combustion engine having a throttle and a spring adapted to open said throttle, manual means for closing said throttle, automatic means for closing said throttle responsive to the suction in the air entrance to said engine, an atmospheric air vent admitting air to said suction responsive means whereby said suction responsive means are rendered inoperative to close the throttle, cen- 10

trifugally operated means for closing said atmospheric air vent, spring means for opposing the centrifugal force, second suction responsive means also responsive to the suction on the engine side of said throttle for weakening the effect of said spring means so as to change the governed speed whereby there are two governed speeds, one for high suction and one for low suction on the engine side of said throttle.

STANLEY M. UDALE.
